UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed March 29, 1927. Serial No. 179,357.

This invention relates to mining machines and more particularly, but not exclusively, to coal mining machines of the continuous cutter flexibly fed type adapted to cut a horizontal kerf in the coal face.

An object of this invention is to provide an improved coal mining machine of the continuous cutter flexibly fed "low vein" type having improved feeding means especially adapted to use with either the longwall or room and pillar systems of mining. Another object of this invention is to provide an improved room and pillar mining machine of extremely low and compact character especially adapted to use in mines having relatively narrow veins of coal. Still another object of this invention is to provide an improved mining machine having an improved cutting mechanism and an improved feeding mechanism, said mechanisms being driven from the opposite ends of the driving motor. A further object of this invention is to provide an improved mining machine of the longwall type having a power driven feed operating member and a power driven controlling or take-up member. Yet another object of this invention is to provide an improved coal mining machine of the invertible type adapted to operate selectively either as an undercutter 30 or as an overcutter. A further object is to provide a coal mining machine of the combined longwall and room and pillar "low vein" type having an improved arrangement of controlling and feeding parts whereby the 35 movement of the machine during cutting in accordance with either system of mining is greatly facilitated. Another object is to provide an improved and simplified plural speed transmission mechanism between the motor and the feed and controlling drums. Still another object of this invention is to provide an improved controlling means for the cutter chain drive which has associated therewith improved locking means for the pivoted cutter bar. A further object is to provide an 45 improved mining machine having an improved compact general arrangement of parts. These and other objects and advantages of this invention will, however, hereinafter more 50 fully appear.

In a preferred form of the invention the objects stated are achieved by providing a coal mining machine of the combined longwall and room and pillar continuous cutter "low vein" type having a plurality of coaxially arranged 55 power driven rope winding drums one of which is for feeding the machine relative to the coal face while the other is operative for controlling the position of the machine relative to the coal face, these drums having their axes vertical and arranged in a novel location and driven from the driving motor in an improved manner. More specifically, a preferred embodiment of the invention may comprise an invertible machine frame 60 slidable on either of two opposed plane surfaces on the mine floor and preferably formed of a feed section, a central motor section and a cutter section, the latter having a projecting cutter bar which is pivotally mounted thereon for 65 horizontal swinging movement and adapted to be locked in a plurality of operative positions relative to the frame. The feeding mechanism preferably comprises a plurality of coaxial winding drums having their axes 70 vertical and disposed at the end of the machine frame remote from the cutting mechanism and these drums are driven at either a fast or a slow speed and at any desired variants of such speeds under the control of a 75 plurality of friction clutches. Flexible feed cables may be attached to and wound upon the feed drums.

In the accompanying drawings in which an illustrative embodiment of the invention is 85 shown,

Fig. 1 is a plan view of the improved mining machine, the cutter bar and feed cables being shown in a plurality of operative positions.

Fig. 2 is a side elevational view of the machine shown in Fig. 1.

Fig. 3 is a longitudinally extending central vertical sectional view taken on line 3-3 of Fig. 1 and illustrating the improved cutting 95 mechanism and cutter bar lock.

Fig. 4 is a longitudinally extending vertical sectional view taken on line 4-4 of Fig. 1 and illustrating the improved feeding mechanism.

Fig. 5 is a detail sectional view illustrating 100

the cutter chain clutch and the improved bar locking means associated therewith, the controlling parts being shown in a plurality of operative positions.

5 Fig. 6 is a detail view of the cutter chain controlling clutch and bar lock shown in Fig. 5.

Fig. 7 is a transverse horizontal detail sectional view taken substantially on line 7-7 10 of Fig. 4.

Fig. 8 is a transverse horizontal sectional view illustrating the feed gearing, parts being shown in plan.

15 Fig. 9 is a transverse vertical sectional view taken substantially on line 9-9 of Figs. 4 and 8.

Fig. 10 is an end elevational view of the feeding end of the improved mining machine.

20 Fig. 11 is a detail view illustrating a portion of the controlling clutch for the feeding drums.

Fig. 12 is a transverse vertical sectional view taken substantially on line 12-12 of Fig. 8.

25 Fig. 13 is a detail sectional view taken on line 13-13 of Fig. 8.

Fig. 14 is a fragmentary plan view partially broken away in section to facilitate illustration and illustrating details of the 30 feeding mechanism.

Fig. 15 is a diagrammatic view illustrating the improved machine when cutting in accordance with the room and pillar system of mining, the machine being shown cutting from right to left.

Fig. 16 is a diagrammatic view illustrating the machine when cutting in accordance with the longwall system of mining.

40 Fig. 17 is a diagrammatic view illustrating the machine mounted on a truck and operating as an entry cutter.

In this illustrative embodiment of the invention there is shown a mining machine designated as an entirety by the reference character 1 and which is herein of the flexibly fed continuous cutter type adapted to cut either according to the longwall or the room and pillar systems of mining. The machine 1 comprises an invertible frame 2 presenting parallel plane surfaces 3 and 4 upon which the machine is adapted to be selectively supported during cutting, thereby to enable the machine to operate either as an undercutter or an overcutter. Pivottally mounted at 45 one end of the machine frame 2 on a vertical axis as at 5 is an elongated plane horizontal cutter bar 6 about the margin of which a cutter bit carrying cutter chain 7 is adapted to be circulated. The cutter bar 6 is adapted 50 to be locked in different positions with respect to the machine frame, the cutter bar being adapted to be held either in a position extending longitudinally of the machine frame or at right angles to the frame and at either 55 side thereof. Feeding of the machine may be

accomplished by either of two flexible feeding elements, here in cables or ropes 8 and 9, each wound upon a feed operating member, herein in the form of coaxially arranged winding drums having their axes vertical and disposed at the end of the machine frame opposite from the cutter bar 6, the drums being respectively designated 10 and 11. During longwall cutting the upper feed drum 11 and the feed cable 9 may preferably be 70 employed, while during room and pillar cutting the feed drum 11 and the feed cable 9 may be used to effect feed, while the other feed drum 10 and feed cable 8 will be used to control the angular position of the machine relative to the coal face.

Referring more particularly to the machine, it will be noted that the same herein comprises three sections, i. e. a motor section 12 which herein comprises a motor casing and bottom plate supporting the motor casing in elevated position, a feed section 13 and a cutter carrying section 14, the feed and cutter sections being herein disposed at opposite ends of the motor section and rigidly connected to the latter in such manner as to form a rigid and very low compact frame 35 slideable on the mine floor. It will be particularly noted that herein the upper and lower surfaces 4 and 3 of the frame sections are preferably disposed in common planes in such manner as to unite to form a single shoe adapted to permit free movement of the machine thereon over the mine floor.

In specifically describing the improved cutting mechanism it will herein be noted that housed within the motor section 12 is an electric motor, herein preferably of the reversible type having its armature shaft 15 horizontally disposed and extending longitudinally of the machine. Fixed by a key and screw connection 16 to one end of the armature shaft 15 (see Fig. 3) is a bevel pinion 18 which meshes with a horizontally disposed larger bevel gear 19 herein preferably formed integral with a vertically disposed hollow shaft 20, the latter being journaled in ball bearings 21 suitably carried by the cutter section 14 of the machine frame. As shown, fixed to and rotatable 40 with the bevel gear 19 is a spur pinion 22 which meshes with a larger spur gear 23 having a cylindrical hub portion 24 journaled on ball bearings 25 herein preferably surrounding and supported by a vertical stud 26. As shown in Fig. 3 the stud 26 is threadedly connected at its opposite end as at 27 to detachable cap members 28 and 29, respectively, these caps being secured to the machine frame by bolts 30. 45 The cap 28 is herein carried by a detachable top cover plate 31, while the cap 29 is carried by a detachable bottom plate 32. It will herein be noted that the caps 28, 29 and plates 31, 32 may be detached from the 50

machine frame to permit axial withdrawal of the vertical stud 26 and gear 23 from the frame thereby facilitating assembly and dismantling of the machine. As illustrated, 5 the cylindrical sleeve portion of the gear 23 is connected by a semi-permanent clutch 33 to a spur gear 34 having a hub portion surrounding and rotatably mounted on the vertical stud 26. Rotatably mounted on 10 the hub of the spur gear 34 and aligned therewith is a spur gear 35 connected, as by a semi-permanent clutch 36 to the cylindrical hub of a cutter chain drive sprocket 37. As shown in Fig. 3 the cutter chain drive 15 sprocket 37 is rotatably mounted on ball bearings 38 surrounding and supported by the vertical stud 26. The hub portion of the gear 34 is interposed between the lower bearing 25 for the gear 23 and the upper bearing 38 for the sprocket 37. The bearings 38 and the sprocket 37 are maintained in operative position by means of a cup-shaped member or step bearing 39 held in position by the bottom plate and to which 25 the bolts 30 are threadedly connected. The vertical stud 26 is suitably pinned to the cap member 28 and the step bearing 39 to prevent rotation of the stud. Cooperating with the member 39 is a depending annular portion 39^a herein formed integral with the cutter frame section 14. Disposed on opposite 30 sides of the cutter chain sprocket 37 and carried respectively by the cup-shaped member 39 and the annular portion 39^a are oil retaining rings 40, these rings preventing leakage of oil from the interior of the machine and also preventing the entry of dirt or other foreign substances to the internal mechanism. Formed in the frame section 40 41 is a vertical bore 41 within which is vertically reciprocable a cylindrical clutch 42 connected at 43 to an internal gear clutch member 44 having teeth which are adapted to cooperate with the 45 teeth of the spur gears 34 and 35 as will later be pointed out. The cutter bar 6 is mounted for swinging movement on bearing sleeves 45 and 46, the latter being supported on the member 39, while the former 50 surrounds a cylindrical portion on the machine frame. Secured by bolts 47 to the cutter bar 6 is a bearing and locking ring 48 herein preferably composed of two parts to facilitate assembly. The locking ring 48 55 is provided with a recess 49 to which one of the feed cables is connectible to effect swinging of the cutter bar. Also formed in the locking ring 48 is a plurality, herein three, of locking recesses or grooves 50. The locking ring 48 is herein rotatably mounted on a two-part bearing sleeve 51 supported on a cylindrical flange 52 herein formed integral with the machine frame, the bearing sleeve 45 also engaging the flange 52. The 60 improved operating mechanism for the cutter chain clutch 44 and the improved bar locking means associated therewith specifically comprises (see also Figs. 5 and 6) 65 70 75 80 85 90 95 100 105 As shown in the drawings, the improved feeding mechanism specifically comprises a spur pinion 75 fixed to the end of the armature shaft 15 opposite from the bevel pinion 18 which drives the cutter chain (see Figs.

4, 8, 9 and 12). The motor pinion 75 meshes with a spur idler gear 76 keyed as at 77 to a horizontal shaft 78 extending longitudinally of the machine and disposed parallel with the motor shaft 15. As shown in Fig. 8, the shaft 78 is journaled at its opposite ends in suitable ball bearings 79 carried within the feed frame section 13. The gear 76 in turn meshes with a spur gear 80 keyed as at 81 to a horizontal shaft 82 disposed in the same horizontal plane with the shafts 15 and 78. As illustrated, the shaft 82 is journaled at its opposite ends in ball bearings 83 suitably carried by the feed frame section. The shaft 82 has preferably formed integral therewith a bevel pinion 84 which meshes with a bevel gear 85 keyed at 86 to a horizontal shaft 87 arranged transversely of the machine in advance of the shafts 15, 78 and 82. The shaft 87 has secured thereto at its inner end by a key 88 a spur gear 89, the hub of the latter being internally bored at 90 to receive a ball bearing 91. The bearing 91 is supported by a projecting stud or dowel 92 suitably secured by screws 93 within the feed frame section. It will also be observed that the bevel gear 85 is internally bored at 94 to receive a ball bearing 95, the latter being likewise supported by a projecting stud or dowel 96 secured by screws 97 to the side of the frame section 13.

Referring more particularly to Fig. 9 it will be noted that the spur gear 89 meshes with a spur gear 98 keyed at 99 to a shaft 100 disposed above and parallel with the shaft 87. The gears 89 and 98 are change speed gears and it is obvious that these gears may readily be removed from their respective shafts and replaced by gears of different tooth ratio to obtain different predetermined feeding speeds. As shown, the inner end of the shaft 100 is journaled through a ball bearing 101 carried within a bore 102 formed within the hub of the gear 98. The opposite end of the shaft 100 is journaled in a ball bearing 103 suitably carried within a detachable bearing bracket 104. The bearing 101 and bracket 104 are supported on dowel pins 105, 106, respectively, similar to the dowel pins 92 and 96 heretofore described. It will herein be observed that by providing the detachable dowel pins 92, 96, 105 and 106 it is possible to remove the shafts 87 and 100 from their supports with facility, these dowel pins also providing an exceedingly stable bearing and supporting structure for the shafts. Moreover, it will be noted that upon removal of the top plate and dowel pins the shafts may be lifted bodily from the machine with facility. The shafts 87 and 100 have respectively rigidly secured thereto intermediate their ends worms 107 and 108, the former having oppositely inclined teeth of steeper lead than the teeth of the latter. The worms

107 and 108 rotate in opposite directions. As clearly shown in Fig. 12 the worms 107 and 108 mesh respectively with worm gears 109 and 110, the latter being coaxially arranged and disposed on a vertical axis. The worm gears 109 and 110 each have hub portions respectively journaled on ball bearings 111 and 112 suitably carried by the machine frame. As shown, the hub portions of the gears 109, 110 each carry spaced alined ball bearings 113 within which the opposite ends of a vertically disposed shaft 114 are journaled. The shaft 114 has herein preferably formed integral therewith intermediate its ends an elongated spur pinion 115 which meshes with a spur gear 116 connectible, in a manner to be later described, to a vertically disposed shaft 117 disposed in the longitudinal center of the machine and journaled at its upper end in ball bearings 118 positioned by a detachable cover plate 119. The shaft 117 has secured thereto by a key 120 a spur pinion 121 having a hub portion journaled in a ball bearing 122 suitably carried by the frame section 13. The pinion 121 is held on the shaft 117 by a bolt 122a extending centrally through the shaft, the bolt having a flange at its upper end engaging the inner race of the ball bearing 118 and being threaded to the pinion at its lower end. The spur pinion 121 is adapted to drive the feed drums 10 and 11 in a novel manner to be later described.

Improved mechanism is provided for alternatively frictionally connecting the fast and slow speed worm gears 109, 110 to the shaft 114 and this mechanism specifically comprises a pivoted shipper yoke 123 (see Figs. 8 and 12) carrying at its inner end suitable rollers 124 which are adapted to engage the plane surfaces of axially movable cylindrical clutch applying members or pressure plates 125 and 126. The members 125 and 126 have projecting fingers extending through apertures in spider members 127 and 128 positioned within the gears 109 and 110, respectively, by means of radially expansible split rings 129. The rings 129 are seated within annular grooves 130 formed within the worm gears. As clearly shown in Fig. 12 the members 127 and 128 are each provided with internal gear teeth 131 which are interlocked with the teeth at the ends of the pinion 115. Furthermore, each of the members 127, 128 carries a series of clutch discs 132 which are interleaved with a corresponding series of clutch discs 133 carried by the hub of the worm gears 109 and 110. In accordance with the illustrative form of the invention the outer end of the shipper yoke 123 is provided with a bifurcated portion 134 straddling an enlarged portion 135 of a vertically disposed rod 136 threadedly connected at its lower end within the machine frame, the enlarged portion 135 having flattened sides which engage the inner

sides of the bifurcated portion 134. The bifurcated portion 134 is provided with arcuate or rounded ends which engage upper and lower transverse yokes 137 and 138, respectively, engaging the upper and lower surfaces of the enlarged portion 135 of the rod. The lower yoke 138 has threadedly connected thereto bolts 139 which engage coiled springs 140 carried within recesses 141 formed in the upper yoke 137. It will thus be evident that the bifurcated member 134 and the resiliently connected yoke 137, 138 form a yieldable pivotal mounting for the shipper yoke 123, the coiled springs 140 being adapted to yield upon overload of either of the controlling clutches 132, 133. Improved means is provided for swinging the shipper yoke 123 about its pivot comprising a crank pin or eccentric 142 (see Fig. 8) formed integral with a rotatable rod 143 journaled at its opposite ends within bearings suitably carried by the frame section 13. Secured to the outer end of the rod 143 by a key 144 is an operating handle 145 conveniently located at the end of the machine. Rotation of the rod 143 is limited by a pin and slot connection 146. It will accordingly be evident that rotation of the handle 145 and consequently the eccentric 142 effects swinging movement of the shipper yoke 123 and consequently one or the other of the controlling clutches 132, 133 connecting the worm gears 109, 110 to the shaft 114 is applied, causing rotation of the latter at either a fast speed or at a slow speed in the same direction. The crank pin or eccentric 142 locks the shipper yoke 123 in either its raised or lowered position when the center of the eccentric passes the vertical center of the rod 136.

Improved clutch mechanism is provided for connecting the spur gear 116 to the shaft 117 and this clutch mechanism as shown in the drawings specifically comprises external clutch teeth 147 formed on a flanged portion 148 of the shaft 117. As shown in Figs. 4 and 12, internal clutch teeth 149 are formed on a clutch ring 150 movably mounted in a recess formed within the gear 116 and these clutch teeth engage clutch teeth 151 formed on the gear 116. The clutch teeth 149 are adapted to cooperate with the clutch teeth 147 as hereinafter described. It will herein be observed that the clutch ring 150 is retained within the recess in the gear 116 by means of a radially expandable split ring 152 disposed within an internal groove 153 formed within the gear 116. The retaining ring 152 presents a projecting shoulder with which a radial flange 154 on the clutch ring 150 is adapted to engage. The clutch ring is normally yieldably maintained against the retaining ring 152 by means of coiled springs 155. As shown in Figs. 4, 8, 11 and 12 secured within the frame section 13 by screws 156 which also hold the cap member 119 in position, is an annular member 157 centrally

cut away at 158 to receive the hub of the spur gear 116 and the shaft 117. Furthermore, the side of the member 157 is cut away as at 159 to clear the upper worm gear 110. The member 157 is provided with a depending flanged portion 160 having formed therein inclined cam slots 161 (see Fig. 11) with which radially located pins 162 carried by a rotatable shipper ring 163 cooperate, the shipper ring carrying a series of rollers 164 which engage the upper plane surface of the clutch ring 150 as clearly shown in Fig. 12. The shipper ring 163 is provided with laterally projecting lugs or teeth 165 with which a tooth or lug 166 formed on a horizontal rod 167 cooperates. The rod 167 is axially movable transversely of the machine and guided at its opposite ends in bores 168 formed in the machine frame. Rotative movement of the rod 167 is prevented by means of a pin and slot connection 169. As illustrated, the rod 167 has threadedly connected thereto an adjustable eye member 170 which is pivotally connected (see also Fig. 10) as at 171 to a lever 172, the latter in turn being pivotally connected intermediate its ends at 173 to the machine frame. The lever 172 is provided with a grasping portion 174 disposed adjacent the handle 145. Thus it will be evident that when the operator grasps the portion 174 and swings the lever 172 about its pivot, the rod 167 is moved axially and the clutch ring 163 is consequently rotated. Rotation of the clutch ring 163 causes the pins 162 carried thereby to move downwardly within the inclined cam slots 161 consequently moving the clutch ring 150 downwardly and interlocking the clutch teeth 149 with teeth 147 as well as 151, thereby connecting the gear 116 to the shaft 117.

As pointed out above the pinion 121 is adapted to drive the feed drums 10 and 11 in an improved manner. Referring more particularly to Fig. 4 it will be observed that the pinion 121 meshes with an internal gear 176 formed integral with the upper feed drum 11. The hub 177 of the feed drum 11 is rotatably mounted on spaced alined ball bearings 178 supported by a central upstanding sleeve portion 179 formed integral with the lower feed drum 10. The hub portion 179 is rotatably mounted by ball bearings 180 suitably carried by the frame section 13, the lower bearing 180 being carried by a detachable bottom plate 181. The bottom plate 181 is rigidly secured to the frame section 13 by suitable means including a vertical stud 182, the latter passing coaxially through the hub 179. As shown in Fig. 4, interposed between the hub 177 of the drum 11 and the hub 179 of the drum 10 is an oil retaining ring 183, while interposed between the lower drum 10 and the bottom plate 181 is a similar oil retaining ring 184. In this instance, the hub of the feed drum 11 has

keyed thereto at 185 a driver member 186 herein in the form of a spider having radially projecting fingers 187. Referring more particularly to Fig. 7 it will be observed that 5 the fingers 187 have inclined surfaces 188 which cooperate with corresponding inclined surfaces 189 formed on clutch or brake shoes 190. Each of the brake shoes 190 carries a strip of braking material 191 interposed between 10 the outer surfaces of the brake shoes and the smooth inner periphery 192 of the lower feed drum 10. The brake shoes 190 each have formed on the inner surface thereof an arcuate eccentric or cam surface 193 15 with which a pressure roll 194 cooperates, the rolls being rotatably mounted on vertical pins 195 carried by a control wheel 196 rotatably mounted on the hub of the driver member 186 and interposed between the feed drums 10 and 11. Thus it will be seen that 20 when the control wheel 196 is grasped by the operator and manually rotated the pressure rolls 194 move along the eccentric surfaces 193 on the brake shoes, forcing the latter outwardly, thereby causing the lower feed drum 10 to be frictionally connected to the upper feed drum 11 for rotation therewith. It will also be obvious that upon suitable release of the control wheel the lower 25 feed drum 10 may be disconnected from the upper feed drum 11 at will during rotation of the latter. When the driver member 186 is rotated with the drum 10 under load the inclined surfaces 188 on the fingers 187 act 30 against the inclined surfaces 189 of the brake shoes, forcing the latter outwardly thereby applying the brake and supplementing the action of the pressure rolls 194. It will further be obvious that the feed drums 35 10 and 11 may be rotated together or remain idle while the gear 121 continuously rotates by suitable application of the clutch 147, 149 and 151. Moreover, when the clutch 147, 149, 151 is connected and upon application of 40 the clutches 132, 133 controlling connection of the worm gears 109 and 110 to the shaft 114, the feed drums 10, 11 may be rotated at a relatively slow speed or at a relatively high speed, the drums rotating in the same direction 45 at both speeds. As shown in Fig. 1, in order to permit cutting according to the room and pillar method a guide sheave or swing arm 200 is provided having a mounting 201 pivotally carried by a bracket 202 50 whereby it may be secured to the machine frame by a suitable dowel 203 (see Fig. 1) and a cooperating bolt 204 adjacent the cutter bar end of the machine and this guide sheave can be shifted from side to side of the 55 machine frame, depending upon the direction of cut desired. Referring to Figs. 4, 8 and 10 it will be observed that the outer end of the feed frame section 13 is cut away as at 205 to permit the gear 116 to mesh with 60 a truck driving gear of any suitable form, 65

thereby to enable the mining machine to drive the wheels of its transport truck in a well known manner. It will also be noted that mounted at each side of the feed drums 10 and 11 on vertical axes at the opposite corners of the machine frame are guide rolls 10 206 rotatably mounted on vertical studs 207 and these rolls are adapted to guide the feed cables 8 and 9 during the various operations of the machine. The motor housed with the frame section 12 is adapted to be controlled by any suitable controlling mechanism including a controlling handle 208 conveniently located opposite the feed control handle 145. 75

In the operation of the improved mining machine when operating in accordance with the longwall system of mining the feed cable 9 may be extended along the side of the machine as indicated by dotted lines in Fig. 1 80 and attached in a suitable manner to a two-part hook connected to the recess 49 in the locking ring 48. The operator then grasps the handle 72 and releases the locking member 69 from the locking groove 50, the clutch 90 34, 35 and 44 being connected at that time. The operator then manipulates the handle 145 applying the slow speed clutch 132, 133 and connecting the slow speed worm gear 110 to the shaft 114. The clutch 147, 149, 151 is then 95 connected and consequently the feed drum 11 is rotated, winding in the feed cable 9 and swinging the cutter bar 6 about its pivot 5. When the cutter bar assumes a position at 100 right angles to the machine frame as indicated by dotted lines in Fig. 1 the operator again manipulates the handle 72, rotating the locking member 69 and moving the latter within one of the locking grooves 50 rigidly locking the cutter bar to the machine frame. The feed cable 9 and the hook are then 105 detached from the locking ring 48 and the cable is then extended around one of the guide sheaves 206 to a point in advance of the machine frame, the free end of this cable being anchored in a suitable manner. The hand wheel 145 is then appropriately manipulated by the operator and the clutch 132, 133 applied, thereby causing the feed drum 11 to 110 wind in the cable and the machine is fed at a cutting speed under friction control. If it is desired to angle the machine during cutting, for instance if a sulphur ball or other unduly hard substance is encountered, the cable 9 is extended in a suitable manner to a 115 suitable anchor. The feed cable is then wound in at a desired speed, thereby causing the machine frame to be swung angularly relative to the coal face. It will be obvious that the cutter bar 6 may be swung to the opposite side of the machine frame and rigidly locked to the latter and upon reversal of the 120 motor, reversal of the cutter bits in their respective links, and the feed cables being wound reversely on their respective drums 125 130

the machine may be fed in an opposite direction as indicated in Fig. 16.

During the operation of the machine in accordance with the room and pillar system of mining, it will be noted that the cutter bar is locked in alinement with the longitudinal axis of the machine frame as indicated by full lines in Fig. 1. The feed cable 9 is extended from the upper feed drum 11 to a suitable roof jack at the right hand rib. The fast speed clutch 132, 133 is then applied and the clutch 147, 148, 149 connected and the cable is wound in at a fast speed thereby moving the machine to the full line position shown in Fig. 15. The feed cable 9 is then extended from the upper feed drum 11 around one of the guide rolls 206 longitudinally of the machine frame and around the front guide sheave 200 forwardly to a point in advance of the machine and suitably anchored to a jack at the coal face as shown in Fig. 15. The receding cable 8 is extended from the lower feed drum 10 around the other guide roll 206 to a suitable jack at the right hand rib, it being assumed that the machine is in the full line position as shown in Fig. 15. The operator then manipulates the handle 145 and the slow speed clutch 132, 133 is loaded and then upon suitable manipulation of the control wheel 196 the feed drums are rotated, winding in the cables 8 and 9, moving the machine forwardly and summing the cutter bar beneath the coal face, the feed drum 10 maintaining the desired controlling tension on the cable 8 at that time. The machine is then straightened up in the usual manner and fed transversely of the face, the feed cable 9 moving the machine laterally while the receding cable 8 maintains the machine in position. If it is desired to angle the machine during cutting, for instance if a sulphur ball is encountered the control wheel 196 is suitably manipulated causing the feed drum 10 to be connected to the feed drum 11 for rotation therewith and consequently the receding cable 8 is wound in thereby moving the rear end of the machine rearwardly and angling the cutter bar. If it is desired to angle the machine in the opposite direction the feed drum 10 is disconnected from the feed drum 11 and the receding cable 8 slackened, thereby permitting the feed drum 11 to swing the rear end of the machine forwardly, thereby angling the cutter bar in the opposite direction. After the transverse cut is completed, the machine is then angled and retracted from the face in a well known manner under the control of the feed drums 10 and 11. It will herein be noted that if it is desired to cut in the opposite direction, that is from left to right the cables 8 and 9 may be reversed on their drums and extended in an opposite manner, the guide sheave 200 transposed to the opposite side of the machine frame, the cutter bits turned in their respective links and the

motor reversed. Furthermore, it will be noted that if desired the improved mining machine may operate while mounted on a transport truck as shown in Fig. 17, the forward end of the truck being cut away to permit free swinging movement of the cutter bar during entry driving. These and other uses and operations of the improved mining machine will be clearly apparent to those skilled in this art.

As a result of this improved construction it will be observed that an exceedingly compact machine vertically is produced, the improved construction in fact enabling the room and pillar machine having a total height of less than sixteen inches to be produced, a much lower room and pillar machine than has heretofore been put on the market and one which is accordingly adapted to use in even the lowest commercially workable veins in room and pillar mining. Furthermore, by reason of the provision of a machine equally adapted to be operated on its top or its bottom, it will be noted that while retaining this low characteristic, a machine is produced which is equally well adapted to use as an overcutter or an undercutter, depending upon the circumstances in the particular mine. Moreover, attention is directed to the fact that the control mechanism for the feed is exceedingly simple, involving only a single control handle capable of being operated quickly and easily by the operator at his station at the end of the machine frame remote from the cutter bar where it will also be noted that the controlling member for the motor and the control clutch for the feed drums are likewise conveniently located, these three controlling elements being the only members which in ordinary operation along the face it is necessary for the operator to use. As for the cutting mechanism, attention is here also directed to the fact that through the improved cutter chain clutch control and the bar locking means associated therewith it is possible to lock the cutter bar and control the cutter chain clutch by but a single control handle. As for the feeding mechanism by reason of the improved arrangement of the same, it will be observed that it is not only possible to reduce the manufacturing cost by reducing the number of parts, but to enable the whole mechanism to be readily accessible whenever desired. It will also be noted that by the improved arrangement of the relatively large feeding drums and driving gearing therefor including the worm gearing it is made possible to compact the feeding mechanism vertically to a marked degree and that at the same time that this is made possible it is also made possible to provide comparatively large friction clutches of ample capacity well adapted to stand up under the most severe demands of service.

While I have in this application specifically

ly described one form of which my invention may assume in practice, it will be understood that this form of the same is shown for purposes of illustration and that the 5 invention may be modified and embodied in various other forms without departing from its spirit or the scope of the appended claims.

What I claim as new and desire to secure by Letters Patent is:

10. 1. In a mining machine, a machine frame slidable on its bottom on the mine bottom and carrying a horizontal motor having its axis extending longitudinally of the machine, cutting mechanism driven from one end of said motor, and feeding mechanism driven from the opposite end of said motor for feeding the machine bodily laterally over the mine bottom including coaxially arranged relatively rotatable feed operating members each adapted to be driven by said motor and cooperating flexible feeding means including advance and receding flexible feeding portions extending in opposite directions from opposite ends of said frame and cooperating with said feed operating members respectively.

20. 2. In a mining machine, a horizontal motor having its axis extending longitudinally of the machine, cutting mechanism driven from one end of said motor, and feeding mechanism driven from the opposite end of said motor including coaxially arranged relatively rotatable feed operating members disposed on a vertical axis and each adapted to cooperate with flexible feeding means.

30. 3. In a mining machine, a horizontal motor having its axis extending longitudinally of the machine, cutting mechanism driven from one end of said motor including a horizontal swingable cutter bar, and feeding mechanism driven from the opposite end of said motor including coaxially arranged relatively rotatable feed operating members disposed on a vertical axis and each adapted to cooperate with flexible feeding means.

40. 4. In a mining machine, a machine frame presenting parallel plane surfaces upon which the machine is adapted to be selectively supported during cutting, a horizontal motor in said frame having its axis extending longitudinally of the machine, cutting mechanism driven from one end of said motor, and feeding mechanism driven from the opposite end of said motor including coaxially arranged relatively rotatable feed operating members each adapted to cooperate with flexible feeding means and disposed on a vertical axis and operative to feed the machine when supported on either surface of said frame.

50. 5. In a mining machine, a machine frame presenting parallel plane surfaces upon which the machine is adapted to be selectively supported during cutting, a horizontal motor in said frame having its axis extending longitudinally of the machine, cutting mechanism

driven from one end of said motor including a horizontally swingable cutter bar, and feeding mechanism driven from the opposite end of said motor including coaxially arranged relatively rotatable feed operating members each adapted to cooperate with flexible feeding means and disposed on a vertical axis and operative to feed the machine when supported on either surface of said frame.

6. In a mining machine, a machine frame slidable on its bottom on the mine bottom and carrying a horizontal motor having its axis extending longitudinally of the machine, cutting mechanism driven from one end of said motor, and feeding mechanism driven from the opposite end of said motor for feeding the machine bodily laterally over the mine bottom including a pair of relatively rotatable feed operating members, one of said feed operating members being connectible to the other for rotation therewith and cooperating flexible feeding means including advance and receding flexible feeding portions extending in opposite directions from opposite ends of said frame and cooperating with said feed operating members respectively.

7. In a mining machine, a horizontal motor having its axis extending longitudinally of the machine, cutting mechanism driven from one end of said motor, and feeding mechanism driven from the opposite end of said motor including coaxially arranged relatively rotatable feed operating members disposed on a vertical axis and each adapted to cooperate with flexible feeding means, and plural speed driving gearing for said feed operating members.

8. In a mining machine, a horizontal motor having its axis extending longitudinally of the machine, cutting mechanism driven from one end of said motor, and feeding mechanism driven from the opposite end of said motor including coaxially arranged relatively rotatable feed operating members disposed on a vertical axis and each adapted to cooperate with flexible feeding means, plural speed driving gearing for rotating one of said feed operating members at a plurality of speeds, and means for connecting the other feed operating member to said power driven feed operating member for rotation therewith.

9. In a mining machine, a motor, and feeding mechanism driven by said motor including a pair of relatively rotatable feed operating members each adapted to cooperate with flexible feeding means, plural speed driving gearing for rotating one of said members at a plurality of speeds, and means operable at will during feeding of the machine for either disconnecting said feed operating members or connecting the other feed operating member to said power driven feed operating member for rotation therewith in the same direction and at the same angular velocity as said

power driven feed operating member rotates.

10. In a mining machine, a motor, and feeding mechanism driven thereby including coaxially arranged relatively rotatable feed operating members each adapted to cooperate with flexible feeding means, plural speed driving gearing for rotating one of said feed operating members at a plurality of speeds, and means operable at will during feeding of the machine for connecting the other feed operating member to said power driven feed operating member for rotation therewith.

11. In a mining machine, a motor, and feeding mechanism driven thereby including coaxially arranged relatively rotatable feed operating members each having its axis vertical and adapted to cooperate with flexible feeding means, plural speed driving gearing for rotating one of said feed operating members at a plurality of speeds, and means operable at will during feeding of the machine for connecting the other feed operating member to said power driven feed operating member for rotation therewith.

25 12. In a mining machine, a motor, and feeding mechanism driven by said motor including a plurality of relatively rotatable feed operating members, each adapted to cooperate with flexible feeding means, plural speed driving gearing for rotating one of said feed operating members at different speeds in the same direction, and means operable at will during feeding of the machine for disconnecting said feed operating members or connecting said feed operating members together for simultaneous rotation in the same direction and at the same angular rate.

30 13. In a mining machine, a driving motor, and feeding mechanism driven thereby including coaxially arranged relatively rotatable feed operating members, each adapted to cooperate with flexible feeding means and driving connections between said motor and said feed operating members comprising worms rotatable on transversely extending horizontal axes, and worm gears constantly meshing therewith and selectively operable as driving members for said feed operating members.

35 14. In a mining machine, a motor, and feeding means driven thereby including coaxially arranged relatively rotatable feed operating members each rotatable on a vertical axis, and adapted to cooperate with flexible feeding means, and driving connections between said motor and said feed operating members comprising worms rotatable on transversely extending horizontal axes, and worm gears constantly meshing therewith and selectively operable as driving members for said feed operating members.

40 15. In a mining machine, a motor, and feeding means driven thereby including coaxially arranged relatively rotatable feed

operating members each adapted to cooperate with flexible feeding means, and driving connections between said motor and said feed operating members comprising worms rotatable on transversely extending horizontal axes, worm gears constantly meshing therewith and selectively operable as driving members for said feed operating members, and speed controlling clutches arranged coaxially with said worm gears.

45 16. In a mining machine, a motor, and feeding means driven thereby including coaxially arranged relatively rotatable feed operating members each rotatable on a vertical axis and adapted to cooperate with flexible feeding means, and driving connections between said motor and said feed operating members comprising worms rotatable on transversely extending horizontal axes, worm gears constantly meshing therewith and selectively operable as driving members for said feed operating members, and speed controlling clutches arranged coaxially with said worm gears.

50 17. In a mining machine, a motor and feeding means driven thereby including coaxially arranged relatively rotatable feed operating members, each adapted to cooperate with flexible feeding means, and driving connections between said motor and said feed operating members comprising worms rotatable on transversely extending horizontal axes, worm gears constantly meshing therewith, and selectively operable as driving members for said feed operating members, and means for alternatively connecting said worm gears in driving relation with said feed operating members.

55 18. In a mining machine, a motor, and feeding means driven thereby including coaxially arranged relatively rotatable feed operating members each rotatable on a vertical axis and adapted to cooperate with flexible feeding means, and driving connections between said motor and said feed operating members comprising worms rotatable on transversely extending horizontal axes, worm gears constantly meshing therewith and selectively operable as driving members for said feed operating members, and means for alternatively connecting said worm gears in driving relation with said feed operating members.

60 19. In a mining machine, a motor, and feeding means driven thereby including coaxially arranged relatively rotatable feed operating members each adapted to cooperate with flexible feeding means, and driving connections between said motor and said feed operating members comprising worms rotatable at different speeds on transversely extending horizontal axes, and worm gears constantly meshing therewith and selectively operable as driving members for said feed operating members.

65 20. In a mining machine, a motor, and feeding means driven thereby including coaxially arranged relatively rotatable feed

20. In a mining machine, a motor, and feeding means driven thereby including coaxially arranged relatively rotatable feed operating members each rotatable on a vertical axis and adapted to cooperate with flexible feeding means, and driving connections between said motor and said feed operating members comprising worms rotatable at different speeds on transversely extending horizontal axes, and worm gears constantly meshing therewith, and driven thereby at different speeds and selectively operable as driving members for said feed operating members.

21. In a mining machine, a motor, and feeding means driven thereby including coaxially arranged relatively rotatable feed operating members, each adapted to cooperate with flexible feeding means, driving connections between said motor and said feed operating members comprising worms rotatable at different speeds on transversely extending horizontal axes, worm gears constantly meshing therewith and selectively operable as driving members for said feed operating members, and speed controlling clutches arranged coaxially with said worm gears.

22. In a mining machine, a motor, and feeding means driven thereby including coaxially arranged relatively rotatable feed operating members each rotatable on a vertical axis and adapted to cooperate with flexible feeding means, driving connections between said motor and said feed operating members comprising worms rotatable at different speeds on transversely extending horizontal axes, worm gears constantly meshing therewith, and selectively operable as driving members for said feed operating members, and speed controlling clutches arranged coaxially with said worm gears.

23. In a mining machine, a motor, feeding means driven thereby including coaxially arranged relatively rotatable feed operating members each adapted to cooperate with flexible feeding means, and driving connections between said motor and said feed operating members comprising worms rotatable on transversely extending horizontal axes, worm gears constantly meshing therewith, a spur gear arranged coaxially with said worm gears and connected in driving relation with said feed operating members, and means for alternatively connecting said worm gears in driving relation with said spur gear.

24. In a mining machine, a motor, feeding means driven thereby including coaxially arranged relatively rotatable feed operating members each rotatable on a vertical axis, and adapted to cooperate with flexible feeding means, and driving connections between said motor and said feed operating members comprising worms rotatable on transversely extending horizontal axes, worm gears constantly meshing therewith, a spur gear arranged coaxially with said worm gears and con-

nected in driving relation with said feed operating members, and means for alternatively connecting said worm gears in driving relation with said spur gear.

25. In a mining machine, a horizontal motor having its axis extending longitudinally of the machine, and feeding means driven thereby including a plurality of relatively rotatable feed operating members each adapted to cooperate with flexible feeding means, and driving connections between said motor and said feed operating members comprising worms rotatable on transversely extending horizontal axes, and worm gears constantly meshing therewith and selectively operable as driving members for said feed operating members.

26. In a mining machine, a motor, and feeding means driven thereby including a plurality of relatively rotatable feed operating members each adapted to cooperate with flexible feeding means, and driving connections between said motor and said feed operating members comprising worms rotatable on transversely extending horizontal axes, worm gears meshing therewith, a spur gear arranged coaxially with said worm gears, a spur gear connected in driving relation with one of said feed operating members and meshing with said first mentioned spur gear, means for alternatively connecting said worm gears in driving relation with said first mentioned spur gear, and means for connecting said feed operating members together for simultaneous rotation.

27. In a mining machine, a motor, and feeding means driven thereby including a plurality of coaxially arranged relatively rotatable feed operating members each adapted to cooperate with flexible feeding means, and driving connections between said motor and said feed operating members comprising worms rotatable on transversely extending horizontal axes, worm gears meshing therewith, a spur gear arranged coaxially with said worm gears, a spur gear connected in driving relation with one of said feed operating members and meshing with said first mentioned spur gear, means for alternatively connecting said worm gears in driving relation with said first mentioned spur gear, and means for connecting said feed operating members together for simultaneous rotation.

28. In a mining machine, a motor, and feeding means driven thereby including a plurality of coaxially arranged relatively rotatable feed operating members each rotatable on a vertical axis and adapted to cooperate with flexible feeding means, and driving connections between said motor and said feed operating members comprising worms rotatable on transversely extending horizontal axes, worm gears meshing therewith, a spur gear arranged coaxially with said worm gears, a spur gear connected in driving re-

lation with one of said feed operating members and meshing with said first mentioned spur gear, means for alternatively connecting said worm gears in driving relation with said 5 first mentioned spur gear, and means for connecting said feed operating members together for simultaneous rotation.

29. In a mining machine, a motor, and feeding means driven thereby including a 10 plurality of relatively rotatable feed operating members each adapted to cooperate with flexible feeding means, driving connections between said motor and said feed operating members comprising worms rotatable on 15 transversely extending horizontal axes, worm gears meshing therewith, a spur gear arranged coaxially with said worm gears, a larger spur gear connected in driving relation with one of said feed operating members 20 and meshing with said spur gear, means for alternatively connecting said worm gears in driving relation with said first mentioned spur gear, releasable means for connecting said last named spur gear in driving relation 25 with said larger spur gear, and means for connecting said feed operating members together for simultaneous rotation.

30. In a mining machine, a motor, and feeding means driven thereby including a 30 plurality of coaxially arranged relatively rotatable feed operating members each adapted to cooperate with flexible feeding means, driving connections between said motor and said feed operating members comprising worms rotatable on transversely extending horizontal axes, worm gears meshing therewith, a spur gear arranged coaxially with said worm gears, a larger spur gear connected in driving relation with one of said feed operating 35 members and meshing with said spur gear, means for alternatively connecting said worm gears in driving relation with said first mentioned spur gear, a releasable means for connecting said last mentioned spur gear in driving relation with said larger spur gear, and means for connecting said feed operating members together for simultaneous rotation.

31. In a mining machine, a motor, and feeding means driven thereby including a 50 plurality of coaxially arranged relatively rotatable feed operating members each rotatable on a vertical axis and adapted to cooperate with flexible feeding means, driving connections between said motor and said feed operating members comprising worms rotatable on transversely extending horizontal axes, worm gears meshing therewith, a spur gear arranged coaxially with said worm gears, a larger spur gear connected in driving relation with one of said feed operating members and meshing with said spur gear, means for alternatively connecting said worm gears in driving relation with said first mentioned spur gear, a releasable means for con-

nnecting said last named spur gear in driving relation with said larger spur gear, and means for connecting said feed operating members together for simultaneous rotation.

32. In a mining machine, a motor having a motor pinion, and feeding means driven thereby including a plurality of relatively rotatable feed operating members each adapted to cooperate with flexible feeding means, and driving connections between said motor and said feed operating members comprising a spur gear meshing with said motor pinion, a spur gear meshing with said gear, a bevel pinion rotatable with said last mentioned gear, a bevel gear meshing with said bevel pinion and rotatable on a horizontal transversely extending axis, a worm rotatable with said bevel gear, a worm gear meshing with said worm, and driving connections between said worm gear and said feed operating members through which one or both of the latter may be selectively driven.

33. In a mining machine, a motor having a motor pinion, and feeding means driven thereby including a plurality of coaxially arranged relatively rotatable feed operating members each adapted to cooperate with flexible feeding means, and driving connections between said motor and said feed operating members comprising a spur gear meshing with said motor pinion, a spur gear meshing with said gear, a bevel pinion rotatable with said last mentioned gear, a bevel gear meshing with said bevel pinion and rotatable on a horizontal transversely extending axis, a worm rotatable with said bevel gear, a worm gear meshing with said worm, and driving connections between said worm gear and said feed operating members.

34. In a mining machine, a motor having a motor pinion, and feeding means driven thereby including a plurality of coaxially arranged relatively rotatable feed operating members each rotatable on a vertical axis and adapted to cooperate with flexible feeding means, and driving connections between said motor and said feed operating members comprising a spur gear meshing with said motor pinion, a spur gear meshing with said gear, a bevel pinion rotatable with said last mentioned gear, a bevel gear meshing with said bevel pinion and rotatable on a horizontal transversely extending axis, a worm rotatable with said bevel gear, a worm gear meshing with said worm, and driving connections between said worm gear and said feed operating members.

35. In a mining machine, a motor having a motor pinion, and feeding means driven thereby including a plurality of relatively rotatable feed operating members each adapted to cooperate with flexible feeding means, and driving connections between said motor and said feed operating members comprising a spur gear meshing with said

motor pinion, a spur gear meshing with said gear, a bevel pinion rotatable with said last mentioned gear, a bevel gear meshing with said bevel pinion and rotatable on a horizontal transversely extending axis, a worm rotatable with said bevel gear, a worm gear meshing with said worm, and driving connections between said worm gear and said feed operating members through which one or both of the latter may be selectively driven including a manually operable controlling clutch.

36. In a mining machine, a motor having a motor pinion, and feeding means driven thereby including a plurality of coaxially arranged relatively rotatable feed operating members each adapted to cooperate with flexible feeding means, and driving connections between said motor and said feed operating members comprising a spur gear meshing with said motor pinion, a spur gear meshing with said gear, a bevel pinion rotatable with said last mentioned gear, a bevel gear meshing with said bevel pinion and rotatable on a horizontal transversely extending axis, a worm rotatable with said bevel gear, a worm gear meshing with said worm, and driving connections between said worm gear and said feed operating members including a manually operable controlling clutch.

37. In a mining machine, a motor having a motor pinion, and feeding means driven thereby including a plurality of coaxially arranged relatively rotatable feed operating members each rotatable on a vertical axis and adapted to cooperate with flexible feeding means, and driving connections between said motor and said feed operating members comprising a spur gear meshing with said motor pinion, a spur gear meshing with said gear, a bevel pinion rotatable with said last mentioned gear, a bevel gear meshing with said bevel pinion and rotatable on a horizontal transversely extending axis, a worm rotatable with said bevel gear, a worm gear meshing with said worm, and driving connections between said worm gear and said feed operating members including a manually operable controlling clutch.

38. In a mining machine, a motor, and feeding means driven thereby including a plurality of relatively rotatable feed operating members each rotatable on a vertical axis and adapted to cooperate with flexible feeding means, and driving connections between said motor and said feed operating members comprising worm gears, and means for alternatively connecting said worm gears in driving relation with said feed operating members to cause either of the latter to draw in a portion of said flexible feeding means during the feeding operation.

39. In a mining machine, a motor, and feeding means driven thereby including a plurality of relatively rotatable feed oper-

ating members each rotatable on a vertical axis and adapted to cooperate with flexible feeding means, and driving connections between said motor and said feed operating members comprising worm gears, means for alternatively connecting said worm gears in driving relation with said feed operating members, and means for permitting relative rotation between said feed operating members or connecting said members together for simultaneous rotation to cause the latter to simultaneously draw in portions of said flexible feeding means during the feeding operation.

40. In a mining machine, a motor, and feeding means driven thereby including a plurality of relatively rotatable feed operating members each rotatable on a vertical axis and adapted to cooperate with flexible feeding means, driving connections between said motor and said feed operating members, and manually operable frictional means for permitting relative rotation between said feed operating members or for yieldably connecting said members together for simultaneous rotation.

41. In a mining machine, a motor, and feeding means driven thereby including a plurality of coaxially arranged relatively rotatable feed operating members each rotatable on a vertical axis and adapted to cooperate with flexible feeding means, driving connections between said motor and said feed operating members, and manually operable frictional means for permitting relative rotation between said feed operating members or for yieldably connecting said members together for simultaneous rotation.

42. In a mining machine, a motor, and feeding means driven thereby including a plurality of relatively rotatable feed operating members each having its axis vertical and adapted to cooperate with flexible feeding means, and driving connections between said motor and said feed operating members comprising coaxially arranged worm gears, and means for alternatively connecting said worm gears in driving relation with said feed operating members.

43. In a mining machine, a motor, and feeding means driven thereby including a plurality of coaxially arranged relatively rotatable feed operating members each having its axis vertical and adapted to cooperate with flexible feeding means, and driving connections between said motor and said feed operating members comprising coaxially arranged worm gears, and means for alternatively connecting said worm gears in driving relation with said feed operating members.

44. In a mining machine, a motor, and feeding means driven thereby including a plurality of relatively rotatable feed operating members each having its axis vertical and adapted to cooperate with flexible feeding

- means, and driving connections between said motor and said feed operating members comprising coaxially arranged worm gears, means for alternatively connecting said worm gears in driving relation with said feed operating members, and means permitting relative rotation between said feed operating members or for connecting said members together for simultaneous rotation.
45. In a mining machine, a motor, feeding means driven thereby including a plurality of coaxially arranged relatively rotatable feed operating members each adapted to cooperate with flexible feeding means, and driving connections between said motor and said feed operating members each adapted to cooperate with flexible feeding means including a horizontal shaft extending transversely of the machine, a second shaft arranged parallel with and above said shaft, gearing connecting said shafts, fast and slow speed worms carried by said shafts respectively, worm gears meshing with said worms, and means for alternatively connecting said worm gears in driving relation with said feed operating members.
46. In a mining machine, a motor, feeding means driven thereby including a plurality of coaxially arranged relatively rotatable feed operating members each having its axis vertical and adapted to cooperate with flexible feeding means, and driving connections between said motor and feed operating members including a horizontal shaft extending transversely of the machine, a second shaft arranged parallel with and above said shaft, gearing connecting said shafts, fast and slow speed worms carried by said shafts respectively, worm gears meshing with said worms, and means for alternatively connecting said worm gears in driving relation with said feed operating members.
47. In a mining machine, a motor, and feeding means driven thereby including a plurality of coaxially arranged relatively rotatable feed operating members each adapted to cooperate with flexible feeding means, and driving connections between said motor and said feed operating members comprising a horizontal shaft extending transversely of the machine, a second shaft arranged parallel with and above said shaft, gearing connecting said shafts, fast and slow speed worms carried by said shafts respectively, worm gears meshing with said worms, and means including friction clutches arranged coaxially with said worm gears for alternatively connecting the latter in driving relation with said feed operating members.
48. In a mining machine, a motor, and feeding means driven thereby including a plurality of coaxially arranged relatively rotatable feed operating members each having its axis vertical and adapted to cooperate with flexible feeding means, and driving connec-
- tions between said motor and feed operating members comprising a horizontal shaft extending transversely of the machine, a second shaft arranged parallel with and above said shaft, gearing connecting said shafts, fast and slow speed worms carried by said shafts respectively, worm gears meshing with said worms, and means including frictional clutches arranged coaxially with said worm gears for alternatively connecting the latter in driving relation with said feed operating members.
49. In a mining machine, a motor, and feeding means driven thereby including coaxially arranged relatively rotatable feed operating members each adapted to cooperate with flexible feeding means, and plural speed driving means therefor including coaxially arranged worm gears selectively operable to drive said members at different speeds in the same direction.
50. In a mining machine, a motor, and feeding means driven thereby including coaxially arranged relatively rotatable feed operating members each adapted to cooperate with flexible feeding means, fast and slow speed transmission means between said motor and feed operating members including coaxially arranged worm gears, and means for only alternatively connecting said worm gears in driving relation with said feed operating members.
51. In a mining machine, a motor, and feeding means driven thereby including coaxially arranged relatively rotatable feeding operating members each having its axis vertical and adapted to cooperate with flexible feeding means, fast and slow speed transmission means between said motor and feed operating members including coaxially arranged worm gears, and means for only alternatively connecting said worm gears in driving relation with said feed operating members.
52. In a mining machine, a motor, and feeding means driven thereby including a plurality of coaxially arranged relatively rotatable feed operating members each adapted to cooperate with flexible feeding means, and fast and slow speed transmission means between said motor and feed operating members including coaxially arranged worm gears rotatable on a vertical axis and selectively operable to drive said feed operating members at different speeds in the same direction.
53. In a mining machine, a motor, and feeding means driven thereby including a plurality of coaxially arranged relatively rotatable feed operating members each having its axis vertical and adapted to cooperate with flexible feeding means, and fast and slow speed transmission means between said motor and feed operating members including coaxially arranged worm gears selectively operable to drive said members at different speeds in the same direction, said worm gears

being disposed on axes parallel with the axes of said feed operating members.

54. In a mining machine, a motor, and feeding means driven thereby including a plurality of coaxially arranged relatively rotatable feed operating members each adapted to cooperate with flexible feeding means, and fast and slow speed transmission means between said motor and said feed operating members including coaxially arranged worm gears rotatable about a vertical axis, and means for only alternatively connecting said worm gears in driving relation with said feed operating members.

55. In a mining machine, a motor, and feeding means driven thereby including a plurality of coaxially arranged relatively rotatable feed operating members each having its axis vertical and adapted to cooperate with flexible feeding means, and fast and slow speed transmission means between said motor and feed operating members including coaxially arranged worm gears disposed on an axis parallel with the axes of said feed operating members, and means for only alternatively connecting said worm gears in driving relation with said feed operating members.

56. In a mining machine, a motor, and feeding means driven thereby including a plurality of relatively rotatable feed operating members each adapted to cooperate with flexible feeding means, and fast and slow speed transmission means between said motor and said members including parallel worms rotatable on horizontal axes extending transversely of the machine.

57. In a mining machine, a motor, and feeding means driven thereby including a plurality of relatively rotatable feed operating members each adapted to cooperate with flexible feeding means, and fast and slow speed transmission means between said motor and said members including parallel worms rotatable on horizontal axes extending transversely of the machine, and coaxially arranged worm gears meshing with said worms respectively.

58. In a mining machine, a motor, and feeding means driven thereby including a plurality of coaxially arranged relatively rotatable feed operating members each having its axis vertical and adapted to cooperate with flexible feeding means, fast and slow speed transmission means between said motor and said feed operating members including parallel worms rotatable on horizontal axes extending transversely of the machine.

59. In a mining machine, a motor, and feeding means driven thereby including a plurality of coaxially arranged relatively rotatable feed operating members each having its axis vertical and adapted to cooperate with flexible feeding means, fast and slow speed transmission means between said motor and said feed operating members including

parallel worms rotatable on horizontal axes extending transversely of the machine, and coaxially arranged worm gears meshing with said worms respectively.

60. In a mining machine, a motor, and feeding means driven thereby including a plurality of coaxially arranged relatively rotatable feed operating members each having its axis vertical and adapted to cooperate with flexible feeding means, and fast and slow speed transmission means between said motor and said feed operating members including parallel worms rotatable on horizontal axes extending transversely of the machine, coaxially arranged worm gears meshing with said worms respectively, and means for alternatively connecting said worm gears in driving relation with said feed operating members.

61. In a mining machine, a machine frame 85
slidable on its bottom on the mine bottom, and carrying a horizontal motor having its axis extending longitudinally of the machine, cutting mechanism driven from one end of said motor including a pivoted cutter bar adjustable into positions at each side of said frame and lengthwise of said frame, and feeding means driven from the opposite end of said motor including coaxially arranged relatively rotatable feed operating 90
members each adapted to be driven by said motor, and cooperating flexible feeding means for feeding the machine bodily over the mine bottom in any position of said cutter bar and including advance and receding flexible feeding portions cooperating with said feed operating members respectively.

62. In a mining machine, a horizontal motor having its axis extending longitudinally of the machine, cutting mechanism driven from one end of said motor including a pivoted cutter bar adjustable into positions at each side of the machine and lengthwise of the machine, and feeding means driven from the opposite end of said motor for feeding the machine in any position of said bar including coaxially arranged relatively rotatable feed operating members disposed on a vertical axis and each adapted to cooperate with flexible feeding means.

63. In a mining machine, a machine frame 115
slidable on its bottom on the mine bottom and carrying a horizontal motor having its axis extending longitudinally of the machine, cutting mechanism driven from one end of said motor including a horizontal swingable cutter bar, and feeding mechanism driven from the opposite end of said motor for feeding the machine bodily laterally over the mine bottom including coaxially arranged 120
relatively rotatable feed operating members disposed on a vertical axis and each adapted to cooperate with flexible feeding means.

64. In a mining machine, a machine frame 125
presenting parallel plane surfaces upon which 130

the machine is adapted to be selectively supported during cutting, a motor in said frame, cutting mechanism driven by said motor, and feeding means driven by said motor including coaxially arranged relatively rotatable feed operating members disposed on a vertical axis perpendicular to said plane supporting surfaces and adapted to feed the machine when supported on either surface of said frame, said members each being adapted to cooperate with flexible feeding means.

65. In a mining machine, a machine frame presenting parallel plane surfaces upon which the machine is adapted to be selectively supported during cutting, a motor in said frame, cutting mechanisms driven from said motor including a horizontally swingable cutter bar, and feeding mechanism driven from said motor including coaxially arranged relatively rotatable feed operating members disposed on a vertical axis perpendicular to said plane supporting surfaces and adapted to feed the machine when supported on either surface of said frame, said members each being adapted to cooperate with flexible feeding means.

66. In a mining machine, a horizontal motor having its axis extending longitudinally of the machine, cutting mechanism driven from one end of said motor, and feeding mechanism driven from the opposite end of said motor including a pair of coaxial relatively rotatable feed operating members disposed on a vertical axis, driving connections between said motor and the upper feed operating member, and cooperating flexible feeding means including an advance flexible feeding portion cooperating with the upper member and a receding flexible portion cooperating with the bottom member, the bottom one of said feed operating members being connectible to said upper feed operating member for rotation therewith.

67. In a mining machine, a horizontal motor having its axis extending longitudinally of the machine, cutting mechanism driven from one end of said motor including a horizontally swingable cutter bar pivoted on a vertical axis at one end of said frame, and feeding means driven by said motor and disposed at the opposite end of said frame including a pair of relatively rotatable feed operating members, one of said feed operating members being connectible to the other for rotation therewith in the same direction and at the same angular velocity as the latter, and cooperating flexible feeding means including advance and receding flexible feeding portions extending in opposite directions from opposite ends of said frame and cooperating with said feed operating members respectively.

68. In a mining machine, a machine frame slidable on its bottom on the mine bottom and carrying a motor, cutting mechanism driven by said motor, and feeding mechanism driven

by said motor for feeding the machine bodily laterally over the mine bottom including a pair of relatively rotatable feed operating members, plural speed driving gearing for rotating one of said members at a plurality of speeds, means operable at will during the feeding operation for connecting the other feed operating member to said motor driven feed operating member for rotation therewith in the same direction and at the same angular rate as said motor driven feed operating member, and cooperating flexible feeding means including advance and receding flexible feeding portions extending in opposite directions from opposite ends of said frame and cooperating with said feed operating members respectively.

69. In a mining machine, a machine frame slidable on its bottom on the mine bottom and carrying a motor, cutting mechanism driven by said motor, and feeding mechanism driven by said motor for feeding the machine bodily laterally over the mine bottom including a pair of coaxially arranged relatively rotatable feed operating members, plural speed driving gearing for rotating one of said members at a plurality of speeds, means operable at will during the feeding operation for connecting the other feed operating member to said motor driven feed operating member for rotation therewith, and cooperating flexible feeding means including advance and receding flexible feeding portions extending in opposite directions from opposite ends of said frame and cooperating with said feed operating members respectively.

70. In a mining machine, a machine frame slidable on its bottom on the mine bottom and carrying a motor, cutting mechanism driven by said motor, and feeding mechanism driven by said motor for feeding the machine bodily laterally over the mine bottom including a pair of coaxially arranged relatively rotatable feed operating members disposed on a vertical axis, plural speed driving gearing for rotating one of said members at a plurality of speeds, means operable at will during the feeding operation for connecting the other feed operating member to said motor driven feed operating member for rotation therewith, and cooperating flexible feeding means including advance and receding flexible feeding portions extending in opposite directions from opposite ends of said frame and cooperating with said feed operating members respectively.

71. In a mining machine, a machine frame slidable on its bottom on the mine bottom and carrying a motor, cutting mechanism driven by said motor, and feeding mechanism driven by said motor for feeding the machine bodily laterally over the mine bottom including a plurality of relatively rotatable feed operating members, plural speed driving gearing for rotating one of said feed operating mem-

bers at different speeds in the same direction, means operable at will during the feeding operation for connecting said feed operating members together for simultaneous rotation at the same angular rate and in the same direction, and cooperating flexible feeding means including advance and receding flexible feeding portions extending in opposite directions from opposite ends of said frame and cooperating with said feed operating members respectively.

72. In a mining machine, a motor, and feeding means driven thereby including a plurality of relatively rotatable feed operating members each adapted to cooperate with flexible feeding means, driving connections between said motor and said feed operating members, and manually operable frictional means for permitting relative rotation between said feed operating members or for yieldably connecting said members together for simultaneous rotation in the same direction and at the same angular rate.

73. In a mining machine, a motor, and feeding means driven thereby including a plurality of relatively rotatable feed operating members each adapted to cooperate with flexible feeding means, and fast and slow speed transmission means between said motor and said feed operating members including a plurality of worms rotatable on horizontal axes lying in the same vertical plane extending transversely of the machine.

74. In a mining machine, a motor, and feeding means driven thereby including a plurality of relatively rotatable feed operating members each adapted to cooperate with flexible feeding means, and fast and slow speed transmission means between said motor and said feed operating members including parallel worms rotatable on horizontal axes lying in the same vertical plane extending transversely of the machine, and coaxially arranged worm gears meshing with said worms respectively and selectively operable as driving members for said feed operating members.

75. In a mining machine, a motor, and feeding means driven thereby including a plurality of coaxially arranged relatively rotatable feed operating members disposed on a vertical axis and adapted to cooperate with flexible feeding means, fast and slow speed transmission means between said motor and said feed operating members including parallel worms rotatable on horizontal axes lying in the same vertical plane extending transversely of the machine.

76. In a mining machine, a motor, and feeding means driven thereby including a plurality of coaxially arranged relatively rotatable feed operating members disposed on a vertical axis and adapted to cooperate with flexible feeding means, fast and slow speed transmission means between said motor and

said feed operating members including parallel worms rotatable on horizontal axes lying in the same vertical plane extending transversely of the machine, and coaxially arranged worm gears meshing with said worms respectively and selectively operable as driving members for said feed operating members.

77. In a mining machine, a driving motor, and feeding mechanism driven thereby including coaxially arranged relatively rotatable feed operating members each adapted to cooperate with flexible feeding means, and driving connections between said motor and said feed operating members comprising worms having teeth of different lead and rotatable on horizontal axes extending transversely of the longitudinal axis of the machine, and worm gears constantly meshing with said worms and selectively operable as driving members for said feed operating members.

78. In a mining machine, a driving motor, and feeding mechanism driven thereby including coaxially arranged relatively rotatable feed operating members disposed on a vertical axis and each adapted to cooperate with flexible feeding means, and driving connections between said motor and said feed operating members comprising worms having teeth of different lead and rotatable on horizontal axes extending transversely of the longitudinal axis of the machine, and worm gears constantly meshing with said worms and selectively operable as driving members for said feed operating members.

79. In a mining machine, a motor, and feeding mechanism driven thereby including relatively rotatable feed operating members each adapted to cooperate with flexible feeding means, one of said members being operatively connected to said motor while the other member is freely rotatable, and operator controlled clutch means operable at will during the feeding operation and carried by and rotatable with one of said feed operating members for connecting said freely rotatable feed operating member to said motor driven feed operating member for simultaneous rotation therewith in the same direction and at the same angular rate as the latter.

80. In a mining machine, a motor, and feeding mechanism driven thereby including relatively rotatable coaxially arranged feed operating members rotatable about a vertical axis and each adapted to cooperate with flexible feeding means, one of said members being operatively connected to said motor while the other member is freely rotatable, and operator controlled clutch means operable at will during the feeding operation and carried by and rotatable with one of said feed operating members for connecting said freely rotatable feed operating member to said motor

driven feed operating member for simultaneous rotation therewith.

81. In a mining machine, a motor, and feeding mechanism driven thereby including relatively rotatable feed operating members each adapted to cooperate with flexible feeding means, one of said feed operating members being operatively connected to said motor while the other member is freely rotatable, and operator controlled clutch means operable at will during the feeding operation and carried by and rotatable with said motor driven feed operating member for connecting said freely rotatable feed operating member 15 to said motor driven feed operating member for simultaneous rotation therewith.

82. In a mining machine, a motor, and feeding mechanism driven thereby including relatively rotatable feed operating members each adapted to cooperate with flexible feeding means, one of said feed operating members being operatively connected to said motor while the other member is freely rotatable, and clutch means carried by and rotatable with said motor driven feed operating member for connecting said freely rotatable feed operating member to said motor driven feed operating member for simultaneous rotation therewith, and controlling means for said clutch means including a control wheel arranged coaxially with and interposed between said feed operating members.

83. In a mining machine, a pair of relatively rotatable coaxial feed operating members disposed on a vertical axis and each adapted to cooperate with flexible feeding means, power operated driving connections for the upper feed operating member, and operator controlled clutch means operable at will during the feeding operation and housed within the lower feed operating member and rotatable with said upper feed operating member for connecting said feed operating members together for simultaneous rotation.

84. In a mining machine, a pair of relatively rotatable coaxial feed operating members disposed on a vertical axis and each adapted to cooperate with flexible feeding means, power operated driving connections for the upper feed operating member, and clutch means housed within the lower feed operating member and rotatable with said upper feed operating member for connecting said feed operating members together for simultaneous rotation, and controlling means for said clutch means including a control wheel arranged coaxially with and interposed between said feed operating members.

85. In a mining machine, a motor, and machine feeding mechanism driven thereby including relatively rotatable feed operating members each adapted to cooperate with

flexible feeding means, and plural speed transmission means between said motor and said feed operating members including coaxial fast and slow speed terminal gears rotatable about a vertical axis, and friction clutches coaxial with said gears for selectively connecting the same in driving relation with said feed operating members to effect rotation of the latter at a plurality of speeds. 70

86. In a mining machine, a motor, and machine feeding mechanism driven thereby including relatively rotatable feed operating members rotatable about a vertical axis and each adapted to cooperate with flexible feeding means, and plural speed transmission means between said motor and said feed operating members including coaxial fast and slow speed terminal gears rotatable about a vertical axis, and friction clutches coaxial with said gears for selectively connecting the same in driving relation with said feed operating members to effect rotation of the latter at a plurality of speeds. 75 80 85

87. In a mining machine, a motor having its axis extending longitudinally of the machine, cutting mechanism driven from one end of said motor, and feeding mechanism driven from the opposite end of said motor including relatively rotatable feed operating members each adapted to cooperate with flexible feeding means, and plural speed transmission means between said motor and said feed operating members including coaxial fast and slow speed terminal gears rotatable about a vertical axis and friction clutches coaxial with said gears for selectively connecting the same in driving relation with said feed operating members to effect rotation of the latter at a plurality of speeds. 90 95 100

88. In a mining machine, a machine frame 105 slidable on its bottom on the mine bottom and carrying a horizontal motor having its axis extending longitudinally of the machine, cutting mechanism driven from one end of said motor and including an elongated cutter bar projecting lengthwise of the machine during lateral cutting, and feeding means driven from the opposite end of said motor for feeding the machine bodily laterally over the mine bottom including relatively rotatable feed operating and controlling members rotatable on axes parallel to a transverse vertical plane and each adapted to be driven by said motor, cooperating flexible feeding means including advance and receding flexible feeding portions cooperating with said feed operating and controlling members respectively, and driving mechanism for said feed operating and controlling members including driving gears each rotatable about a 115 vertical axis and friction controlling means between each driving gear and said members. 120 125

89. In a mining machine, a machine frame 130 slidable on its bottom on the mine bottom and carrying a horizontal motor having its axis 135

extending longitudinally of the machine, cutting mechanism driven from one end of said motor including a pivoted cutter bar adjustable into positions at each side of said frame and lengthwise of said frame, and feeding means driven from the opposite end of said motor for feeding the machine bodily over the mine bottom in any position of said cutter bar including relatively rotatable feed 10 operating and controlling members each adapted to be driven by said motor and rotatable on axes parallel to a transverse vertical plane, cooperating flexible feeding means including advance and receding flexible feeding portions cooperating with said feed operating and controlling members respectively, and driving mechanism for said feed operating and controlling members including a fast speed frictional controlling 15 device and a slow speed frictional controlling device, said devices being only alternately operable.

90. In a mining machine, a machine frame 25 slidable on its bottom on the mine bottom and carrying a horizontal motor having its axis extending longitudinally of the machine, cutting mechanism driven from one end of said motor including an elongated cutter bar projecting forwardly lengthwise of the machine during lateral cutting, and feeding means driven from the opposite end of said motor for feeding the machine bodily laterally over the mine bottom including coaxially arranged relatively rotatable feed 30 operating and controlling members each adapted to be driven by said motor and disposed on axes parallel to a transverse vertical plane, and cooperating flexible feeding means including advance and receding flexible feeding portions cooperating with said feed operating and controlling members respectively.

91. In a mining machine, a machine frame 45 slidable on its bottom on the mine bottom and carrying a horizontal motor having its axis extending longitudinally of the machine, cutting mechanism driven from one end of said motor including a pivoted cutter bar adjustable into positions at each side of said frame and lengthwise of said frame, and feeding means driven from the opposite end of said motor for feeding the machine bodily over the mine bottom in any position of said cutter bar including coaxially arranged relatively rotatable feed 50 operating and controlling members each adapted to be driven by said motor and rotatable on axes parallel to a transverse vertical plane, and cooperating flexible feeding means including advance and receding flexible feeding portions cooperating with said feed operating and controlling members respectively.

92. In a mining machine, a machine frame 60 presenting parallel plane surfaces upon which the machine is adapted to be selectively sup-

ported during cutting, a motor in said frame, cutting mechanism driven from said motor including a horizontally swingable cutter bar, and feeding means driven from said motor including relatively rotatable feed operating and controlling members rotatable on aligned axes parallel to a transverse vertical plane perpendicular to said plane supporting surfaces and each adapted to be driven by said motor and adapted to move the machine when supported on either surface of said frame, said members each being adapted to cooperate with flexible feeding means.

93. In a mining machine, a horizontal motor having its axis extending longitudinally 70 of the machine, cutting mechanism driven from one end of said motor, and feeding means driven from the opposite end of said motor including a pair of relatively rotatable feed operating and controlling members, driving connections between said motor and one of said members, means for connecting the other of said members to said motor driven feed member for rotation therewith, and co-operating flexible feeding means including an 75 advance flexible feeding portion cooperating with said feed operating member and a receding flexible feeding portion cooperating with said controlling member.

94. In a mining machine, a machine frame 80 slidable on its bottom on the mine bottom and carrying a horizontal motor having its axis extending longitudinally of the machine, cutting mechanism driven from one end of said motor including an elongated cutter bar projecting forwardly lengthwise of the machine during lateral cutting, and feeding means driven from the opposite end of said motor for feeding the machine bodily laterally over the mine bottom including coaxially arranged 85 relatively rotatable feed operating and controlling members each adapted to be driven by said motor, and cooperating flexible feeding means including advance and receding flexible feeding portions cooperating with 90 said feed operating and controlling members respectively.

95. In a mining machine, a motor, and feeding means driven by said motor including relatively rotatable feed operating and controlling members each adapted to cooperate with a separate flexible feeding element and disposed on axes parallel to a transverse vertical plane, and plural speed driving mechanism between said motor and said members for rotating the latter in a direction to draw in their respective feeding elements to effect feed of the machine at a relatively fast haulage speed or a relatively slow cutting speed including a fast speed worm gear train and a slow speed worm gear train each having a worm and worm gear individual thereto, one of said gear trains being disconnected from said members while the other gear train is connected in operative driving relation there- 100

with during driving thereof at either speed.

96. In a mining machine, a motor, and feeding means driven by said motor including relatively rotatable feed operating and controlling members each adapted to cooperate with a separate flexible feeding element and disposed on axes parallel to a transverse vertical plane, and plural speed driving mechanism between said motor and said members including selectively operable fast and slow speed worm gears rotating on axes parallel to said transverse vertical plane, and a friction controlling clutch coaxial with each worm gear for selectively connecting the latter in driving relation with said feed operating and controlling members.
97. In a mining machine, a motor, and feeding means driven by said motor including relatively rotatable feed operating and controlling members each adapted to cooperate with a separate flexible feeding element and disposed on axes parallel to a transverse vertical plane, and plural speed driving mechanism between said motor and said members including selectively operable coaxial fast and slow speed worm gears rotating on axes parallel to said transverse vertical plane, and a friction controlling clutch coaxial with each worm gear for selectively connecting the latter in driving relation with said feed operating and controlling members.
98. In a mining machine, a motor, and feeding means driven by said motor including relatively rotatable feed operating and controlling members each adapted to cooperate with flexible feeding means and disposed on axes parallel to a transverse vertical plane, and plural speed driving mechanism between said motor and said members including coaxial fast and slow speed worm gears rotatable on axes parallel to the axes of said feed operating and controlling members, and a friction controlling clutch coaxial with each worm gear for selectively connecting the latter in driving relation with said feed operating and controlling members.

99. In a mining machine, a machine frame slidable on its bottom directly on the mine bottom, a motor carried by said frame, and feeding means driven by said motor for feeding the machine bodily laterally over the mine bottom including relatively rotatable feed operating and controlling members each adapted to cooperate with flexible feeding means and rotatable on axes parallel to a transverse vertical plane, and plural predetermined speed gearing between said motor and said members including fast and slow speed worm gear trains each including a final worm gear individual thereto and rotatable on an axis parallel to the axes of said feed operating and controlling members, one of said worm gear trains being disconnected from said members while the other gear train is connected in operative driving relation

therewith during driving thereof at either speed.

100. In a mining machine, a machine frame slidable on its bottom directly on the mine bottom, a motor carried by said frame, and feeding means driven by said motor for feeding the machine bodily laterally over the mine bottom including relatively rotatable feed operating and controlling members each adapted to cooperate with a separate flexible feeding element and rotatable on axes parallel to a transverse vertical plane, and plural speed transmission connections between said motor and said members including a fast speed worm gear train, and a slow speed worm gear train each having a worm and worm gear individual thereto, one of said worm gear trains being disconnected from said members while the other gear train is connected in operative driving relation therewith during driving thereof at either speed.

101. In a mining machine, a machine frame slidable on its bottom directly on the mine bottom, a motor carried by said frame, and feeding means driven by said motor for feeding the machine bodily laterally over the mine bottom including relatively rotatable feed operating and controlling members each adapted to cooperate with a separate flexible feeding element, and plural speed driving gearing between said motor and said members including fast and slow speed worm gear trains, each train including a final worm gear individual thereto and rotating on an axis parallel to a transverse vertical plane, one of said worm gear trains being disconnected from said members while the other gear train is connected in operative driving relation therewith during driving thereof at either speed.

102. In a mining machine, a horizontal motor having its axis extending longitudinally of the machine, cutting mechanism driven from one end of said motor, and feeding mechanism driven from the opposite end of said motor including a pair of relatively rotatable feed operating members each disposed on a vertical axis, driving connections between said motor and one of said feed operating members, and cooperating flexible feeding means including an advance flexible feeding portion cooperating with one feed operating member and a receding flexible portion cooperating with the other member, and means operable at will for connecting said latter feed operating member to said motor driven feed operating member for rotation therewith.

103. In a mining machine, a horizontal motor having its axis extending longitudinally of the machine, cutting mechanism driven from one end of said motor, and feeding mechanism driven from the opposite end of said motor including a pair of coaxial relatively rotatable feed operating members, driving

- connections between said motor and the upper feed operating member, and cooperating flexible feeding means including an advance flexible feeding portion cooperating with the upper member and a receding flexible portion cooperating with the bottom member, and means operable at will for connecting said bottom feed operating member to said upper feed operating member for rotation therewith.
104. In a mining machine, a motor, and feeding means driven thereby including a plurality of relatively rotatable feed operating members each adapted to cooperate with flexible feeding means, driving connections between said motor and said feed operating members, and manually operable frictional means operable at will for permitting relative rotation between said feed operating members or for yieldably connecting said members one to the other for simultaneous rotation in the same direction and at the same angular rate.
105. In a mining machine, a motor, and feeding means driven thereby including a plurality of coaxially arranged relatively rotatable feed operating members each adapted to cooperate with flexible feeding means, driving connections between said motor and said feed operating members, and manually operable frictional means operable at will for permitting relative rotation between said feed operating members or for yieldably connecting said members one to the other for simultaneous rotation.
106. In a mining machine, a driving motor, and feeding mechanism driven thereby including relatively rotatable feed operating members each adapted to cooperate with flexible feeding means, flexible feeding portions associated one with each of said members and each having an end connectible extraneously of the machine, and driving connections between said motor and said feed operating members comprising worms rotatable on horizontal axes, and worm gears constantly meshing therewith and selectively operable as driving members for each feed operating member and means for only alternatively connecting said worm gears in driving relation with said feed operating members.
107. In a mining machine, a motor, and feeding means driven thereby including relatively rotatable feed operating members each rotatable on a vertical axis and adapted to cooperate with flexible feeding means, and driving connections between said motor and said feed operating members comprising worms rotatable on horizontal axes, and worm gears constantly meshing therewith and selectively operable as driving members for each feed operating member.
108. In a mining machine, a motor, and feeding means driven thereby including coaxially arranged relatively rotatable feed operating members each rotatable on a vertical axis and adapted to cooperate with flex-

ible feeding means, and driving connections between said motor and said feed operating members comprising worms, and worm gears constantly meshing therewith and selectively operable as driving members for each feed operating member.

109. In a mining machine, a motor, and feeding means driven thereby including relatively rotatable feed operating members each adapted to cooperate with flexible feeding means, flexible feeding portions associated one with each of said members and each having an end connectible extraneously of the machine, and driving connections between said motor and said feed operating members comprising worms rotatable on horizontal axes, worm gears constantly meshing therewith and selectively operable as driving members for each feed operating member, and a speed controlling clutch arranged coaxially with each of said worm gears.

110. In a mining machine, a motor, and feeding means driven thereby including coaxially arranged relatively rotatable feed operating members each rotatable on a vertical axis and adapted to cooperate with flexible feeding means, and driving connections between said motor and said feed operating members comprising worms, worm gears constantly meshing therewith and selectively operable as driving members for each feed operating member, and a speed controlling clutch arranged coaxially with each of said worm gears.

111. In a mining machine, a motor, and feeding means driven thereby including relatively rotatable feed operating members each rotatable on a vertical axis and adapted to cooperate with flexible feeding means, and driving connections between said motor and said feed operating members comprising worms rotatable on horizontal axes, worm gears constantly meshing therewith and selectively operable as driving members for each feed operating member, and a speed controlling clutch arranged coaxially with each of said worm gears.

112. In a mining machine, a motor, feeding means driven thereby including relatively rotatable feed operating members disposed on axes which are parallel to a vertical plane extending transversely of the machine, each of said members being adapted to cooperate with flexible feeding means, and driving connections between said motor and said feed operating members comprising worms, worm gears constantly meshing therewith, a spur gear arranged coaxially with said worm gears and connected in driving relation with each feed operating member, and means for alternatively connecting said worm gears in driving relation with said spur gear.

113. In a mining machine, a motor, feeding means driven thereby including relatively rotatable feed operating members each ro-

- tatable on a vertical axis and adapted to cooperate with flexible feeding means, and driving connections between said motor and said feed operating members, for rotating the latter in a direction to draw in their respective flexible feeding means to effect feed of the machine at a relatively high haulage speed or a relatively low cutting speed, comprising worms, worm gears constantly meshing therewith, a spur gear arranged coaxially with said worm gears and connected in driving relation with each feed operating member, and means for only alternatively connecting said worm gears in driving relation with said spur gear.
114. In a mining machine, a motor, and feeding means driven thereby including a plurality of relatively rotatable feed operating members, each adapted to cooperate with a flexible feeding portion, and driving connections between said motor and said feed operating members comprising worms, worm gears meshing therewith, a spur gear arranged coaxially with said worm gears, a spur gear connected in driving relation with one of said feed operating members and meshing with said first mentioned spur gear, means for alternatively connecting said worm gears in driving relation with said first mentioned spur gear, and means for connecting said feed operating members one to the other for simultaneous rotation.
115. In a mining machine, a motor, and feeding means driven thereby including a plurality of relatively rotatable feed operating members, each adapted to cooperate with a flexible feeding portion, driving connections between said motor and said feed operating members comprising worms, worm gears meshing therewith, a spur gear arranged coaxially with said worm gears, a larger spur gear connected in driving relation with one of said feed operating members and meshing with said spur gear, means for alternatively connecting said worm gears in driving relation with said first mentioned spur gear, releasable means for connecting said last named spur gear in driving relation with said larger spur gear, and means for connecting said feed operating members one to the other for simultaneous rotation.
116. In a mining machine, a motor, and feeding means driven thereby including a plurality of relatively rotatable feed operating members adapted to cooperate with flexible feeding means, and driving connections between said motor and said feed operating members comprising worm gears, means for connecting said worm gears alternatively in driving relation with said feed operating members, and means for permitting relative rotation between said feed operating members or connecting said members one to the other for simultaneous rotation to cause the latter to simultaneously draw in portions of

said flexible feeding means during the feeding operation.

117. In a mining machine, a motor, and feeding means driven thereby including a plurality of relatively rotatable feed operating members each having its axis vertical and adapted to cooperate with flexible feeding means, and driving connections between said motor and each of said feed operating members comprising worm gears, and means for only alternatively connecting said worm gears in driving relation with said feed operating members.

118. In a mining machine, a motor, and feeding means driven thereby including a plurality of relatively rotatable feed operating members adapted to cooperate with flexible feeding means, and driving connections between said motor and each of said feed operating members comprising worm gears, means for connecting said worm gears alternatively in driving relation with said feed operating members, and means permitting relative rotation between said feed operating members or for connecting said members one to the other for simultaneous rotation.

119. In a mining machine, a motor, and feeding means driven thereby including relatively rotatable feed operating members disposed on axes which are parallel to a vertical plane extending transversely of the machine and each adapted to cooperate with a separate flexible feeding element, and plural speed driving means therefor, the driving means for each of said members including worm gears selectively operable to drive said member at different speeds in the same direction and means for only alternatively connecting said worm gears in driving relation with said feed operating members.

120. In a mining machine, a motor, and feeding means driven thereby including relatively rotatable feed operating members disposed on axes which are parallel to a vertical plane extending transversely of the machine and each adapted to cooperate with a separate flexible feeding element, fast and slow speed transmission means between said motor and each of said feed operating members including worm gears, and means for only alternatively connecting said worm gears in driving relation with said feed operating member.

121. In a mining machine, a motor, and feeding means driven thereby including a plurality of relatively rotatable feed operating members each adapted to cooperate with flexible feeding means, and fast and slow speed transmission means between said motor and each of said feed operating members including worm gears rotatable on vertical axes and selectively operable to drive said feed operating member at different speeds in the same direction said feed operating members being driven through only one

worm gear during driving thereof at either speed.

122. In a mining machine, a motor, and feeding means driven thereby including a plurality of relatively rotatable feed operating members each having its axis vertical and adapted to cooperate with flexible feeding means, and fast and slow speed transmission means between said motor and each of said feed operating members including worm gears selectively operable to drive said member at different speeds in the same direction, said worm gears being disposed on axes parallel with the axes of said feed operating members said feed operating members being driven through only one worm gear during driving thereof at either speeds.

123. In a mining machine, feeding means comprising relatively rotatable coaxially arranged haulage drums, power operated driving connections for one of said drums, and operator-controlled clutch means for connecting said drums together for simultaneous rotation, and controlling means for said clutch means including a controlling element interposed between and projecting outwardly from said drums.

124. In a mining machine, feeding mechanism comprising relatively rotatable coaxially arranged haulage drums, power operated driving connections for one of said drums, and operator-controlled clutch means for connecting said drums together for simultaneous rotation, and controlling means for said clutch means operable at will during the feeding operation and including a control wheel arranged coaxially with and interposed between said drums.

125. In a mining machine, feeding means comprising a pair of relatively rotatable haulage drums, and operator-controlled friction clutch means operable at will for connecting said drums together for simultaneous rotation including a clutch drum rotatable with one of said haulage drums, and friction means connected to said other haulage drum and engageable with said clutch drum for connecting said haulage drums together for rotation in the same direction and at the same angular rate.

126. In a mining machine feeding mechanism, a pair of relatively rotatable feed members each adapted to cooperate directly with flexible feeding means and of the same size and diameter and rotatable at the same winding speeds, motor operated devices for rotating one of said members in winding direction, and clutch means operable at will during rotation of said motor driven feed member for connecting said other feed member thereto for simultaneous rotation therewith at the same angular rate and in the same direction.

127. In a mining machine feeding mechanism, a pair of relatively rotatable feed members each adapted to cooperate directly with

flexible feeding means and of the same size and diameter and rotatable at the same winding speeds, motor operated devices for rotating one of said members in winding direction, and clutch means operable at will during rotation of said motor driven feed member for connecting said other feed member thereto for simultaneous rotation therewith at the same angular rate and in the same direction, said clutch means being controllable to permit rotation of said other feed member in winding direction at a speed slower than the winding speed of said motor driven feed member.

128. In a mining machine feeding mechanism, a pair of relatively rotatable feed members each adapted to cooperate directly with flexible feeding means and of the same size and diameter and rotatable at the same winding speeds, motor operated plural speed devices for rotating one of said members in winding direction at either a relatively low speed or at a relatively high speed; and clutch means operable at will during rotation of said motor driven feed member for connecting said other feed member thereto for simultaneous rotation therewith at the same angular rate and in the same direction.

129. In a mining machine feeding mechanism, relatively rotatable feed members each adapted to cooperate directly with flexible feeding means and motor operated plural speed transmission means for effecting rotation of said members at either a relatively low speed or a relatively high speed and including fast and slow speed terminal gears each rotating about a vertical axis, and frictional controlling means for selectively effecting drive through said terminal gears.

130. In a mining machine feeding mechanism, relatively rotatable feed members each adapted to cooperate directly with flexible feeding means and motor operated plural speed transmission means for effecting rotation of said members at either a relatively low speed or a relatively high speed and including coaxial fast and slow speed terminal gears rotating about a vertical axis, and frictional controlling means for selectively effecting drive through said terminal gears.

131. In a mining machine feeding mechanism, relatively rotatable coaxially arranged feed members each adapted to cooperate directly with flexible feeding means and motor operated plural speed transmission means for effecting rotation of said members at either a relatively low speed or a relatively high speed and including coaxial fast and slow speed terminal gears rotating about a vertical axis, and frictional controlling means for selectively effecting drive through said terminal gears.

132. In a mining machine feeding mechanism, relatively rotatable feed members each rotating about a vertical axis and adapted

- to cooperate directly with flexible feeding means and motor operated plural speed transmission means for effecting rotation of said members at either a relatively low speed or a 5 relatively high speed and including coaxial fast and slow speed terminal gears rotating about a vertical axis, and frictional controlling means for selectively effecting drive through said terminal gears.
- 10 133. In a mining machine feeding mechanism, relatively rotatable coaxially arranged feed members rotating about a vertical axis and adapted to cooperate directly with flexible feeding means and motor operated plural speed transmission means for effecting rotation of said members at either a relatively low speed or a relatively high speed and including coaxial fast and slow speed terminal gears rotating about a vertical axis, and frictional controlling means for selectively effecting drive through said terminal gears.
- 15 134. In a mining machine feeding mechanism, relatively rotatable feed members each adapted to cooperate directly with flexible feeding means and motor operated plural speed transmission means for effecting rotation of said members at either a relatively low speed or a relatively high speed and including coaxial fast and slow speed terminal gears rotating about a vertical axis, frictional controlling means for selectively effecting drive through said terminal gears, and clutch means operable at will for disconnecting said feed members from said transmission means 20 to permit free rotation of said feed members.
- 25 135. In a mining machine feeding mechanism, relatively rotatable coaxially arranged feeding members, each adapted to cooperate directly with flexible feeding means, motor operated devices for driving one of said members in winding direction including an internal gear rotatable with one of said members and a motor driven pinion meshing with said internal gear, and clutch means operable at 30 will for connecting said other feed member in driving relation with said internal gear.
- 35 136. In a mining machine feeding mechanism, relatively rotatable coaxially arranged feed members each adapted to cooperate directly with flexible feeding means, and motor operated plural speed transmission means for effecting rotation of said members at either a relatively low speed or a relatively high speed and including coaxial fast and slow speed terminal gears rotating about axes parallel to said feed member axes, and frictional controlling means for selectively effecting drive through said terminal gears.
- 40 137. In a mining machine feeding mechanism, relatively rotatable coaxially arranged feed members each adapted to cooperate directly with flexible feeding means, and motor operated plural speed transmission means for effecting rotation of said members at either a relatively low speed or a relatively high
- speed and including coaxial fast and slow speed terminal gears rotating about axes parallel to said feed member axes, frictional controlling means for selectively effecting drive through said terminal gears, and devices in the drive between said feed members and said transmission means for entirely disconnecting said feed members from their drive to permit free rotation thereof.
- 45 138. In a mining machine feeding mechanism, relatively rotatable coaxially arranged feed members each adapted to cooperate directly with flexible feeding means and motor operated plural speed transmission means for effecting rotation of said members at either a relatively low speed or a relatively high speed and including coaxial fast and slow speed terminal gears rotating about axes parallel to said feed member axes, and friction clutches, one individual to each terminal gear, for selectively effecting drive through said terminal gears.
- 50 In testimony whereof I affix my signature.
MORRIS P. HOLMES.
